UNITED STATES PATENT OFFICE.

ARTHUR L. STEVENS, OF CHICAGO, ILLINOIS.

REGENERATIVE FURNACE.

1,292,126.

Specification of Letters Patent.

Patented Jan. 21, 1919.

Application filed May 19, 1916. Serial No. 98,499.

To all whom it may concern:

Be it known that I, ARTHUR L. STEVENS, a citizen of the United States, residing at Chicago, in the county of Cook and State of Illinois, have invented certain new and useful Improvements in Regenerative Furnaces, of which the following is a specification.

My invention relates to regenerative furnaces, and more particularly to apparatus of the forging furnace type in which there is a working opening leading to the heating chamber which is open constantly during the operation of the furnace, or at least for most of the time.

One of the principal objects of the invention is to provide a furnace of this general type in which a relatively high temperature may be maintained; in which the temperature will be uniform throughout the working chamber; and in which, although there may be a constantly open working opening, excessive air in the heating chamber will be prevented so that the flame will be a neutral or even a reducing flame.

A further object is to provide a furnace in which it is possible to economically use a lean, cold producer gas which has been cleaned to remove the soot and tarry matters which, incidentally, may be saved. By using a clean gas the maintenance cost is reduced.

A further object is to provide an economical and efficient furnace which can be operated without any stack draft and in which the fuel will be completely burned so that there will be no discharge of noxious gases into the room in which the furnace is located.

A further object is to provide a furnace for generating relatively high temperatures, in which the heat developed will be utilized to the fullest extent; that is, a furnace constructed so that the gases issuing from the discharge openings will be at a very low temperature compared with the temperature of the heating chamber.

My invention consists in the novel constructions, arrangements and devices to be hereinafter described and claimed, for carrying out the above stated objects and such other objects as will be mentioned in the following specification.

The invention consists further in a novel and improved method of producing and maintaining a high temperature in an inclosed, or substantially inclosed, space by

means of a neutral or reducing flame. I desire herein to claim this method as such.

The invention is illustrated in the accompanying drawings as embodied in a forging furnace of preferred construction.

Figure 1 shows the furnace in front elevation.

Fig. 2 is a vertical cross sectional view in a plane parallel to the front of the furnace.

Fig. 3 is a sectional view on line 3—3 of Fig. 2.

Fig. 4 is a vertical section and Fig. 5 a sectional plan of one of a pair of preferably identically constructed valves for controlling the supply of gas to the flow of air through the furnace.

Fig. 6 is a plan view of the furnace.

Fig. 7 is an enlarged sectional view on line 7—7 of Fig. 1.

Fig. 8 is a view, in perspective, of one of the exhaust valves, and

Fig. 9 is a diagrammatic vertical sectional view to illustrate the flow of the gases through the supply pipes, flues, working chamber and regenerators.

Like characters of reference indicate like parts in the several figures of the drawings.

I shall describe the preferred construction shown in the drawings but with the understanding that while in matters of detail this particular embodiment of the invention involves some points of novelty, considering the invention more broadly, the principles thereof might be employed, without departure from the scope and objects of the invention as defined in the claims, in a furnace quite different in its design and mechanical construction.

Referring to Figs. 1 to 8 inclusive, the numerals 10 designate corner angle pieces which terminate in legs 11. 12 is a front plate, 13, 13 side plates, and 14 a back plate, all of metal and secured to said corner angle pieces. 15 is a top plate supported on angle bars 16, 16, secured to the front and back plate, respectively. Extending along the top of the side plates are angle bars 17 and along their bottom edges angle bars 18. The latter support a number of transversely arranged T-irons 19 that carry the brick-work of the furnace, a stratum of heat insulating material, for example, cork brick 20 being interposed between the T-irons and the lower courses of the bricks. The heating chamber 21 extends from the

front to the back of the furnace and is reached through a working opening 22 in the brickwork 23 of the front wall of the furnace. The effective size of the working opening is varied by means of a fire brick element 24 which is supported in a casting 25 slotted at 26 so that it may be bolted at different elevations to projecting webs 27 on the front corner pieces 10. The casting 25 is formed with a water chamber 28. 29, 29 are the water pipes which lead to and from the water chamber. The lower portions 30 of the brick side walls are thicker than the upper portions 31 and are formed with horizontal flues 32^a, 32^b leading into the heating chamber, these flues communicating by vertical flues 33^a, 33^b with the regenerators A and B, respectively. A plurality of gas burners 34^a—34^b extend into the flues 32^a, 32^b. 35 is a gas supply pipe having branches 36 leading to the burners. A valve 37 directs the gas either to one side of the furnace or the other, as may be desired. A brickwork arch 38 forms the top of the heating chamber. The hearth is formed by brickwork 39. Above and spaced from the arch 38 is a second arch 40 which supports the checkerwork of the regenerators A, B, and the dividing wall 41 between the regenerators. 30 By the arrangements just described such portions of the brickwork of the hearth may be removed and new bricks put in by removing the supporting T-irons 19. Furthermore, when it is necessary to replace the 35 bricks in the arch 38 this arch may be torn out without disturbing the checkerwork of the regenerators which is supported by the upper arch 40.

The top walls of the regenerators are 40 pierced by a series of relatively large discharge openings 42^a, 42^b which lead directly to the atmosphere. These discharge openings are designed to be covered by slide valves 43 which move on a damper plate 44 45 slidably mounted on the top plate 15 of the furnace. The damper plate has openings 45 and is formed with lugs 46 with threaded perforations to receive set screws 47 which are carried by a flange 48 on the top plate 15. 50 The damper plate may be adjusted by the set screws, which are locked by nuts 49, so as to vary the position of the openings 45 with respect to openings 42, whereby the discharge of gases from the regenerators may 55 be regulated. The valves are formed with forks 50 which are engaged by a rod 51 connected by links 52 to levers 53 rigidly connected with a rock shaft 54 mounted in brackets 55 on one of the side plates of the 60 furnace. The rock shaft is operated by a lever 56. 57, 58 are spacing sleeves surrounding the shaft 51.

59 is the air supply pipe connected with a fan or other suitable air compressor (not 65 shown). The air from pipe 59 is directed by

a valve 60 into one or other of the branch pipes 61^a, 61^b, these pipes being provided each with a number of smaller branch pipes 62^a, 62^b leading into the regenerators through the top wall of the furnace. The 70 valves 37, 60 may be alike in construction, this construction being illustrated in Figs. 4 and 5. The casing of the valve (valve 60 being the one shown and described), is formed with a neck 63 connected with the 75 air supply pipe 59 and with ports 65, 65 communicating with the branch pipes 61. In the ports 65 are arranged spiders 66 slidably supporting the valve body 67 which is provided at opposite ends with studs 68 80 passing through central openings in the spiders, the valve body 67 being provided with two valves 69 and the rims 70 of the spiders forming seats for the valves. The valve body is slotted at 71 to receive the 85 rounded end of a finger 72 which is rigidly secured to a shaft 73. This same shaft carries on its lower end a finger corresponding to the finger 72 which operates the valve body of valve 37. The shaft 73 carries an arm 74 connected by a link 75 with an arm 76 on the shaft 54, the arm 76 being preferably formed with a slot 77, the end of link 75 being in the form of a hook 78 which passes through slot 77. 90

95 By means of these arrangements the fuel and air supply valves and the discharge valves are operated simultaneously by a single movement of lever 56.

In order to extend the hearth 39 a trifle 100 beyond the working opening an angular casting 79 is bolted to webs 80 on the front corner pieces 10 of the furnace. The outer courses of the hearth bricks are supported by casting 79. 105

Operation: In the drawings the furnace is shown as being supplied with fuel and air from the side of regenerator A and exhausting through regenerator B. The gas enters the horizontal ducts 32^a through the 110 gas burners 34^a. Here it meets streams of heated air which are conducted from regenerator A through the vertical flues 33^a. The 115 fresh air is supplied to the regenerator A through branch pipes 61^a, 62^a, under controllable pressure. The products of combustion pass into the regenerator B through flues 32^b, 33^b, and exhaust, directly to the atmosphere, through the exhaust ports 42^b. These exhaust ports have a relatively large 120 aggregate area so that the exhaust gases are discharged freely from the regenerator. Air and gas are introduced into the furnace under pressure. The discharge of 125 burned gases is effected by the difference in weight between the relatively cold air in regenerator A and the highly heated products of combustion in regenerator B through which the furnace is shown as exhausting. In a furnace of this type it is necessary, be- 130

cause of the character of the work performed, to have an opening into the heating chamber which is open constantly during the operation of the furnace. In order to prevent on the one hand air from being drawn into the heating chamber through the working opening or, on the other hand, the flames from escaping therethrough to an undesirable extent the aggregate area of the discharge ports 42^b is calculated with reference to the temperature desired to maintain a pressure in the heating chamber just a trifle above that of the atmosphere. For a furnace intended for one service this will be taken care of in the design of the furnace. Where the furnace is intended for the production of different temperatures the outlet ports will be provided with the adjusting damper herein shown and described by means of which the size of the ports may be varied as required. The result is that no appreciable amount of air enters the heating chamber through the working opening. This is important in order to prevent oxidation of the metal operated upon and to insure against unequal heating of different parts of the chamber. In other words, successful operation depends upon a proper balance of pressures whereby the desired high temperature is maintained in the heating chamber, although constantly open to the atmosphere, and whereby the burned gases are discharged at a low temperature so that fuel is economized. By such operation a neutral or possibly a reducing flame is produced in the heating chamber at a minimum fuel cost, which heats the chamber uniformly throughout. This balance of pressures is made possible by arranging the regenerators above the heating chamber, by making the exhaust openings from the regenerators large and adjustable when the furnace is designed for different services, and by depending upon the regenerator through which the burned gases are escaping to act as a stack; a stack, literally speaking, being entirely superfluous so far as the operation of the furnace is concerned. The air and fuel gas pressures will be so regulated as to supply enough fuel and oxygen to raise the temperature in the heating chamber to the desired point.

By introducing the air and gas into the furnace at intervals along one side of the same and by dividing the fuel, and the air also, into separate currents or jets, the gas from each jet mingling with a definite, confined stream of air, a homogeneous mixture of air and gas is produced which insures a uniform and high temperature by preventing stratification of the fuel.

A single movement of the operating lever shifts all of the controlling valves to positions which produce a reversal of the flow of gases through the furnace; the fuel gas,

in such case, entering ports 32^b through burners 34^b, the air entering the regenerator B through branch pipes 61^b, 62^b and the products of combustion discharging through regenerator A and exhaust ports 42^a.

In a furnace constructed and operated as above described, it is possible to use a lean producer gas and still maintain a relatively high temperature, say twenty-five hundred degrees Fahrenheit, or higher, in the heating chamber. This fuel is cheap. It is possible further to obtain a complete combustion of the fuel so that the exhaust may be discharged directly into the room where the furnace is located, eliminating the necessity of a stack. As another element of economy, the furnace may be operated so as to deliver the discharge gases at a relatively low temperature, say four hundred degrees Fahrenheit, even when the temperature in the furnace is as high as the temperature mentioned. This means a utilization of the heat to the fullest extent and makes it possible to cheapen very considerably the construction of the valves for controlling the exhaust ports. It is not necessary to preheat the gas. There is no provision for passing the gas through regenerators. This simplifies and cheapens the construction of the furnace and makes it much more compact than would otherwise be the case. By reason of the fact that cold gas may be employed it is possible to use, economically, a gas which has been cleaned to remove soot and tarry matters. This reduces the cost of up-keep of the furnace and makes it feasible to save the tarry matters in the gas which are valuable by-products. Cold gas can be handled more cheaply than hot gas because, being smaller in volume, the pipes and valves through which it passes from the producer to the furnace may be made smaller. The use of cold gas also eliminates the water cooling of the valves and ducts.

While large furnaces might be designed according to my invention, I have particularly in mind to provide a fuel burning furnace, of the regenerative type which might be made comparatively small, for use in heating steel for forging purposes, which, in spite of its small size and the employment of an inexpensive fuel, such as lean producer gas, will develop high temperatures. Small furnaces, as heretofore designed, have not been capable of developing high temperatures when cheap fuel, such as producer gas, is used. My invention has resulted in the successful application of the regenerative principle to the small furnace, making it possible to obtain very high temperatures at small construction, up-keep and fuel cost, and without danger of oxidizing the metal operated upon.

I claim:

1. In a furnace, the combination of regen-

1. Regenerators having discharge openings in the top, a plurality of valves slidably arranged so as to be movable from positions closing the openings in one regenerator to positions closing the openings in the other regenerator, a rod extending across said valves and loosely engaged with the same, an operating lever, and connections between said rod and operating lever.
2. In a furnace, the combination with an air supply pipe having branches leading to opposite sides of the furnace, a fuel supply pipe having branches leading to opposite sides of the furnace, valves in each of said pipes, arranged one above the other, and adapted, in each case, to direct the fluid therein to one of the branch pipes, a shaft provided with fingers for operating said valves simultaneously, and means for giving a movement of partial rotation to said shaft.
3. A furnace comprising a heating chamber having a constantly open working orifice, regenerators through which air is introduced into the heating chamber and products of combustion discharged therefrom respectively, in alternation, said regenerators being provided with discharge openings and valves to close the same, means for introducing air under pressure into one of said regenerators at a time and means for varying the effective cross-sectional area of the discharge opening of the regenerator through which the products of combustion are discharged.
4. In a furnace, the combination of regenerators having discharge openings in the top, valves slidably arranged so as to be movable from positions closing the opening in one regenerator to positions closing the opening in the other regenerator, means for operating said valves, and a damper plate to vary the effective areas of said discharge openings.
5. A furnace comprising a heating chamber having a constantly open working orifice, regenerators arranged above said heating chamber through which air is introduced into the heating chamber and products of combustion discharged therefrom respectively, in alternation, said regenerators being provided with discharge openings at their upper ends and valves to close the same, means for introducing air under pressure into one of said regenerators at a time and means for varying the effective cross-sectional area of the discharge opening of the regenerator through which the products of combustion are discharged.
6. In a regenerative furnace, the combination of a heating chamber, a pair of regenerators arranged above said chamber through which in alternation air is introduced into and burned gases are discharged from the heating chamber, means for introducing fuel gas into the chamber, means for forcing air into the chamber through said regenerators alternately; said chamber having a working orifice constantly open to the atmosphere and the regenerators provided at the top with discharge openings for burnt gases; and means for varying the effective size of said discharge openings in accordance with the temperature maintained in said heating chamber whereby a pressure is maintained in the chamber preventing appreciable inflow of air through the working opening without causing any substantial discharge of the products of combustion through said working opening.
7. In a regenerative furnace, the combination of a supporting structure, a hearth and means comprising an arch for constituting a combustion chamber, an arch arranged above said first named arch, and regenerators comprising checkerwork supported on said second named arch.
8. Method of maintaining a high temperature in a chamber having an orifice constantly open to the atmosphere and utilizing the heat of the burnt gases, which consists in introducing air into said chamber and discharging the burnt gases therefrom through heat storing passageways providing air and gas columns which are above the chamber so that the heavier air column overbalances the lighter column of gas, and controlling the discharge of burnt gases in accordance with the temperature in the heating chamber so as to maintain a pressure in said chamber which will prevent appreciable inflow of air through said orifice without causing substantial discharge of products of combustion therefrom.
9. Method of maintaining high temperature in a chamber having an orifice constantly open to the atmosphere and utilizing the heat of the burnt gases, which consists in introducing air into said chamber and discharging the burnt gases therefrom through heat storing passageways providing air and gas columns which are above the chamber so that the heavier air column balances the lighter column of gas; mixing fuel gas, without preheating, with the inflowing air in the form of a plurality of streams at the place where the air passes from the heat storing passageway into the heating chamber and controlling the discharge of burnt gases in accordance with the temperature in the heating chamber so as to maintain a pressure in said heating chamber which will prevent appreciable inflow of air through said orifice without causing substantial discharge of the products of combustion therefrom.
10. In a regenerative furnace, the combination of means constituting a heating chamber, a support for the same, a pair of regenerators arranged above the heating chamber having discharge openings in the

- top for the products of combustion and flues communicating with opposite sides of the heating chamber, respectively, a gas main arranged under the heating chamber having a plurality of branch pipes leading to each of the aforesaid flues, an air supply main above the regenerators having branches for introducing air into the upper ends of the regenerators, respectively, valves in said 10 air and gas mains, valves whereby said discharge openings in the regenerators may be opened and closed, and apparatus for operating said valves so air may be introduced into the chamber through first one 15 regenerator and then the other and mixed with gas introduced into the furnace from the same side, while the products of combustion are discharged through the other regenerator in each case.
- 20 11. In a regenerative furnace, the combination of means constituting a heating chamber, a support for the same, a pair of regenerators arranged above the heating

chamber having discharge openings in the top for the products of combustion and flues communicating with opposite sides of the heating chamber, respectively, a gas main arranged under the heating chamber having a plurality of branch pipes leading to each of the aforesaid flues, an air supply main above the regenerators having branches for introducing air into the upper ends of the regenerators, respectively, valves in said air and gas mains, valves whereby said discharge openings in the regenerators may be 25 opened and closed, apparatus for operating said valves so air may be introduced into the chamber through first one regenerator and then the other and mixed with gas introduced into the furnace from the same side, while the products of combustion are 30 discharged through the other regenerator in each case, and means for varying the effective size of the discharge openings in the regenerators, for the purpose described.

ARTHUR L. STEVENS.
